WATER HEATER

Filed Sept. 7, 1923

INVENTOR
WILLIAM COLEBROOK

By *W. Colebrook, Jr.* Atty.

UNITED STATES PATENT OFFICE.

WILLIAM COLEBROOK, DECEASED, LATE OF DURBAN, NATAL, SOUTH AFRICA; BY
HILDER MARY MAY COLEBROOK, OF HARRINGAY, AND LUCY ANNE NEALE, OF
GRANTHAM, ENGLAND, EXECUTRIXES.

WATER HEATER.

Application filed September 7, 1923. Serial No. 661,533.

To all whom it may concern:

Be it known that WILLIAM COLEBROOK, late a subject of the King of Great Britain and Ireland, but now deceased, and a resident of Durban, Natal, South Africa, did during his lifetime invent a certain new and useful Improvement in Water Heaters, of which the following is a specification.

This invention relates to apparatus for 10 heating water by electricity, of the type in which the electric current is passed through a resistance tape coiled outside of a metal cylinder whose inner surface is in contact with the water to be heated.

15 The object of the invention is to provide a simple and cheap construction which shall not readily get out of order.

The invention comprises an iron or other suitable cylinder closed and outwardly 20 flanged at each end and coated on its outer surface with vitreous enamel. On the vitreous enamel is wound a spiral of resistance tape, the ends of which are bound to the cylinder by circular bands connected 25 to suitable terminals. Over the tape is applied a layer of mica which is tightly held in place by armouring of suitable metal (preferably copper) wire, and the whole is enclosed in an outer shell-like cylinder 30 which is secured to the flanges and spaced away from the resistance element. Within this space may be placed a layer of suitable heat-insulating material. The water to be heated passes through the interior of 35 the iron or the like cylinder. An inner cylinder may be provided between which and the former the water may be caused to travel in a hollow cylindrical path.

In cases where the water is passed through 40 the heater from a circulating tank for the purpose of heating water in bulk, and in other cases under certain conditions I prefer to dispense with the inner cylinder.

Practical modes of carrying out the invention, showing preferred constructional features, are hereinafter described with reference to the accompanying drawings, wherein:—

Figure 1 is a sectional elevation of one 50 form of apparatus.

Figure 2 is an exterior view of a form modified so far as the outside electrical connections are concerned.

Referring to the drawings, α is the main

cylinder of the apparatus, which is of metal, 55 and electrically insulated by a coating of vitreous enamel on the exterior, the interior also being enamelled to protect the iron cylinder. This enamel b is represented by the double line shown in the drawings. 60 The resistance tape c is applied over the enamel and there is a soft metal wire armouring wound round with an intervening mica insulation. In the view according to Figure 1, the leads d from such resistance 65 winding (suitably beaded or otherwise insulated) are led to a terminal box e . In Figure 2 I show an alternative arrangement of leads which are taken to the recessed back of a baseboard f and wired so that the switch 70 g acts as a local current cut-off at the apparatus, whilst connection with a source of power is made through the plug socket h . Also, in said Figure 2 i represents a water 75 inlet control valve. In connection with the switches and water valve, I wish it to be understood that any suitable interworking device may be incorporated so that the water valve cannot be closed without switching off the current. 80

The main cylinder α is formed integrally with end flanges j , and both ends are closed, one end by a detachable cover plate k . Such closed ends have central apertures to provide a water passage at l and m . An outer 85 shell-like cylinder n surrounds the main cylinder and its windings, and the assembly is mounted by brackets o to a baseboard f .

In the sectional view, Figure 1, I have shown a form of apparatus where the water 90 enters at l and travels in hollow cylindrical fashion to the outlet for hot water at m . The water passage is formed by an interior closed cylinder p spaced away from the main cylinder α by studs q , and having castellated ends r which space and position it longitudinally in the apparatus. 95

I claim:

1. A water heater of the class described comprising a main cylinder having offset 100 flanges at opposite sides thereof and closed at one end, a water inlet at the closed end, a cap for the open end, a hollow closed cylinder having castellated end portions fitting within the main cylinder and providing a 105 relatively constricted annular water passage between the outside of the interior closed cylinder and the inside wall of the main cyl-

inder, a water outlet communicating with the chamber formed by one of the castellated ends of the closed inner cylinder, electrical heating wires carried by the outside of the 5 said main cylinder, and a protecting shell engaging with the flanges of said main cylinder.

2. A water heater of the class described comprising a main cylinder closed at one 10 end and having offset flanges at opposite ends thereof, electrical heating means surrounding the outside of said main cylinder, a water inlet for the closed end of the cylinder, a cap for the upper end of said cylinder and

having the water outlet connection, means 15 within the main cylinder forming a relatively constricted water passage, brackets for engaging with the flange portions of the main casing for supporting the device, and an encasing shell also engaging with 20 said flanges.

In testimony whereof we have affixed our signatures hereto.

HILDE MARY MAY COLEBROOK,
LUCY ANNE NEALE,

Executrices of the Last Will and Testament of William Colebrook, Deceased.
